UNITED STATES PATENT OFFICE.

VICTOR ANGERER, OF RIDLEY PARK, PENNSYLVANIA, ASSIGNOR TO WILLIAM WHARTON, JR., & COMPANY, INCORPORATED, OF PHILADELPHIA, PENNSYLVANIA, A CORPORATION OF PENNSYLVANIA.

RAILWAY-SWITCH.

No. 807,801.

Specification of Letters Patent.

Patented Dec. 19, 1905.

Application filed September 13, 1905. Serial No. 278,286.

To all whom it may concern:

Be it known that I, VICTOR ANGERER, a citizen of the United States, residing in Ridley Park, Pennsylvania, have invented certain improvements in Railway-Switches, of which the following is a specification.

My invention relates to certain improvements in railway-switches in which the outside switch-rail extends over the main rail when the switch is set for siding or turnout.

The object of my invention is to so construct the outside switch-rail that it will be substantial and will not wear away rapidly.

In the accompanying drawings, Figure 1 is a plan view of a railway-switch, illustrating my invention. Fig. 2 is a sectional view on the line 2 2, Fig. 1. Fig. 3 is a sectional view on the line 3 3, Fig. 1; and Fig. 4 is a detached perspective view of the point-section of one of the switch-rails.

A A' are the rails of the main track. B B' are the rails of the turnout, and D D' are the switch-rails, which are continuations of the rails B B'. The switch-rails are connected together by tie-rods *d* and can be moved against or away from the rails A A' by any suitable shifting mechanism. The rail D' is a point-rail, which rests against the inner side of the main rail A', while the rail D not only rests against the outer side of the rail A, but also laps over the head of the rail, so as to carry the wheel from the main rail to the siding as it is forced over by the point-rail D'.

In order to strengthen the point portion of the switch-rail D, I recess the rail *d'* and insert therein a hard-metal piece E, preferably of manganese steel, forming a point-section. This point-section is shaped as illustrated in Fig. 4, having a vertical body portion, which is secured to the web of the rail D by rivets or bolts, and a side flange *e*, which tapers from the point to the rear. The point portion *e'* of this flange *e* is beveled, as shown, to form a thin surface directly at the point and to provide sufficient metal a short distance back of the point to carry the load. Projecting outward at the base of the body portion are feet *e*², which are secured to the base-flange of the rail D by rivets or bolts, and these feet rest upon the slide-plates *c*, secured to the ties *C*. In place of the separate feet, as shown in Fig. 4, a single foot-flange may extend the full length of the strengthening-

piece E when additional strength is required.

By my invention I can use an ordinary T-headed rail for the outside switch-rail, recess it at *d'*, and secure to the rail a separate piece shaped to the desired form, and when necessary this piece can be readily removed and another piece secured in its place.

I claim as my invention—

1. The combination in a railway-switch, of a main rail, a switch-rail, a point-section secured to one side of the switch-rail at the outer end thereof, said point-section having a flange extending from its upper edge and arranged to lap over the main rail when the switch-rail is moved against said main rail.

2. The combination in a railway-switch, of a main rail, a switch-rail, a hard-metal point-section secured to one side of the switch-rail at the outer end thereof, said point-section having a flange at its upper edge, and a foot extending under the switch-rail.

3. The combination in a railway-switch, of a main rail, a switch-rail notched at its outer end, a hard-metal point-section secured to the notched portion of the switch-rail and having a flange extending from its upper edge and arranged to lap over the main rail and having a laterally-extending foot-section, substantially as described.

4. The combination in a railway-switch, of a main rail, a switch-rail notched at one side, a point-section secured to the notched portion of the switch-rail and having a lateral flange at its upper edge in line with the head of the switch-rail and arranged to lap over the main rail and tapered at the point end and having a series of feet extending under the switch-rail and forming supports, substantially as described.

5. The combination in a railway-switch, of a main rail, a switch-rail, a hard-metal point-section secured to that side of the switch-rail adjoining the main rail, said point-section having a flange extending from the upper edge at one side, and having a foot at the opposite side extending under the switch-rail.

In testimony whereof I have signed my name to this specification in the presence of two subscribing witnesses.

VICTOR ANGERER.
